(57) **CLAIM**

The ornamental design for a light emitting diode, as shown and described.

DESCRIPTION

FIG. 1 is a top perspective view of an LED showing our design;

FIG. 2 is a top view thereof;

FIG. 3 is a top end view thereof;

FIG. 4 is an opposing bottom end view thereof;

FIG. 5 is a bottom view thereof opposite the view of FIG. 2;

FIG. 6 is a side view thereof;

FIG. 7 is an opposing side view thereof; and,

FIG. 8 is a back perspective view thereof.

The broken lines immediately adjacent to the shaded areas represent the boundaries of the claimed design. Other broken lines are for illustrative purpose only and form no part of the claimed design. None of the broken lines form part of the claimed design.
